(57) **CLAIM**

The ornamental design for a mould for casting, as shown and described.

DESCRIPTION

1. Mould for casting
- 1.1 : top perspective view;
- 1.2 : side view;
- 1.3 : side view;
- 1.4 : side view;
- 1.5 : top view;
- 1.6 : bottom view;
- 1.7 : side view.

The features covered by the gray overlay in FIGS. 1.3, 1.4 and 1.6 show portions of the mould for casting that form no part of the claimed design.
